VENETIAN BLIND STRUCTURE

Edward E. Schaefer, Oak Park, Ill., assignor to
Theodore Efron, Chicago, Ill.

Application March 10, 1949, Serial No. 80,734

5 Claims. (Cl. 160—173)

1

This invention relates to an improved Venetian blind structure and more particularly to a novel means for detachably securing slat-supporting tapes to the upper and lower rails of a Venetian blind.

In the conventional Venetian blind construction a horizontal upper tilting rail is provided and secured thereto are a plurality of depending slat-supporting tapes, e. g. ladder tapes comprising pairs of parallel tapes connected at regular intervals by cross-linking rungs. The horizontal slats of the blind are supported by the rungs of the ladder tapes, and the tapes are secured at their lower ends to a horizontal bottom rail. A tilting mechanism is provided for tilting the upper rail to open and close the slats of the blind. Operating cords for raising and lowering the blind extend downwardly through openings in the slats and are fastened to the bottom rail.

Venetian blinds, as is well known to housewives and other users thereof, require periodic cleaning and washing, particularly when the blinds are finished in light colors. Although Venetian blinds are available in which the slats are removable for cleaning purposes, no means has ordinarily been provided for readily removing the slat-supporting tapes. In the usual construction, the tapes are more or less permanently secured to the upper and lower rails, for example, by nails, screws, staples, or other fastening means. As a result, it is only with considerable difficulty that the slat-supporting tapes can be removed for cleaning, and the removal procedure involves the danger of tearing the ends of the tapes and the necessity of replacing the nails, screws, staples, or other fastening means when the blind is reassembled. Accordingly, readily detachable slat-supporting tapes are a highly desirable adjunct to the modern Venetian blind thereby permitting soiled tapes to be removed for cleaning or dyeing when it is desired to change the color.

One object of the present invention is to provide a Venetian blind construction in which the slat-supporting tapes may be readily removed for cleaning or dyeing and may be reassembled with ease.

A further object of the invention is to provide a tape-securing bracket for attachment to a rail of a Venetian blind by means of which the slat-supporting tapes may be detachably secured to said rail.

An additional object of the invention is to provide a tape-securing bracket for attachment to the rail of a Venetian blind which is of such

construction that it can be made from relatively light gauge metal and yet is readily adapted to support the load to which it is subjected without bending or deformation.

5 Still another object of the invention is to provide a tape-securing bracket adapted to be attached to a rail of a Venetian blind by means of which both the slat-supporting tapes and the raising and lowering cords of the blind may be 10 detachably secured to the rail whereby to permit the blind to be readily dismantled and reassembled.

A still further object of the invention is to provide a tape-securing bracket for attachment to 15 the rail of a Venetian blind which avoids undesirable creases, wrinkles, or bellying in the tapes and effects a smooth, attractive, and unbellied appearance.

Other objects and advantages of the invention 20 will be evident upon reference to the accompanying drawings and the detailed description thereof.

Fig. 1 is a fragmentary front elevational view 25 of a Venetian blind showing a bracket comprising one specific embodiment of my invention as used in conjunction with the lower rail of the blind;

Fig. 2 is an end view taken along the lines 30 2—2 of Fig. 1 and showing the bracket in side elevation and the bottom rail in cross-section;

Fig. 3 is an enlarged top plan view of the bracket taken along the lines 3—3 of Fig. 1;

Fig. 4 is a transverse cross-sectional view taken 35 along the lines 4—4 of Fig. 3; and

Fig. 5 is a fragmentary perspective view of the bracket and rail showing the manner of manipulating the bracket during attachment or detachment of the tapes.

The particular form of tape-securing bracket 40 depicted in the drawing for purposes of illustration is shown as mounted on the bottom rail of a Venetian blind. However, it will be understood that the bracket may be used with equally satisfactory results on the top rail of the blind.

45 The bracket, indicated generally at 10, is secured in a rectangular recess or pocket 11 which is cut out of the top surface of a bottom rail 12. By means hereinafter described in detail, the lower ends of a slat-supporting tape comprising front and rear tape members 13 and 14 are 50 detachably secured to the bracket 10. The usual transverse rungs indicated at 16 extend between the tape members 13 and 14 for supporting the slats of the blind as indicated at 17. A cord 18 for raising and lowering the blind extends down-

55

wardly through openings in the slats 17 between the tape members 13 and 14 and is detachably secured at its lower end, by means hereinafter described in detail, to the bracket 10. It will thus be seen that the bracket 10 detachably secures both the slat-supporting tape and the cord of the blind to the bottom rail, it being understood that a similar combination of bracket, tape, and cord is provided at the opposite end of the blind in the customary manner.

The bracket 10 comprises a body member having a flat central portion or fastening plate 19 provided with a pair of spaced apertures to permit attachment of the bracket by means of a pair of screws 21 to the bottom of the recess 11 in the rail 12. Depending downwardly at each end of the central portion 19 and extending laterally on each side thereof are elongated parallel legs or flanges 22, the bottom edges of which abut the bottom of the recess 11 whereby to position the portion 19 in substantially coplanar or flush relation with the upper surface of the rail 12, and the end faces of which abut the sides of the recess 11. The central portion 19 of the bracket is also provided with a keyhole slot 23 having a portion 24 at one end of relatively large diameter and a longitudinally extending portion 25 of lesser width. The elongated portion 25 is of slightly tapering conformation with the narrowest dimension being at the juncture of the portions 24 and 25, as indicated at 26.

Projecting inwardly from the top edges of the flanges 22, and in laterally spaced coplanar relationship with respect to the central portion 19, is a pair of opposed tape-securing arms 27 and 28 which are integral with the flanges 22. As best seen in Fig. 3, the arms 27 and 28 extending toward each other from the oppositely disposed flanges 22 are of different lengths, the arm 28 being shorter than the arm 27, and the innermost free ends of the arms 27 and 28 are spaced from each other as indicated at 29. A corresponding pair of tape-securing arms 30 and 31 is provided at the opposite side of the central portion 19 with the free ends thereof being spaced as at 32. Instead of the two piece construction shown in the drawing, I may also provide single arms extending across the bracket and secured at only one end thereof to one of the flanges 22.

The opposite ends of the flanges 22 are formed at their upper edges with inwardly extending tabs or ears 33 and 34 which are coplanar with the central portion 19 and with the tape-securing arms and are spaced from the latter. An elongated tape-engaging side member in the form of a bar 36 of U-shaped cross-section is pivotally secured at one end to one of the ears 34 by means of a pin or rivet 37 and is swingable about the pin 37 toward and away from the bracket. The upper and lower sides of the bar 36 are slightly pinched or crimped toward each other at the free end, as indicated at 38 in Fig. 5, whereby when the bar 36 is in closed position, the corresponding ear 33 may be received in tight fitting recessed relation within the bar 36 for retaining the same in closed position. A similar tape-engaging bar 39 is pivotally mounted on the other ear 34 on the opposite side of the bracket 10 and coacts in the same manner with the other ear 33.

The ends of the tape members 13 and 14 are stitched as at 40 to form loops 41, as seen most clearly in Fig. 4, through which the pairs of tape-securing arms 27, 28 and 30, 31 are inserted for attaching the tapes to the bracket 10. The

clearance or space 29 between the free ends of the arms 27 and 28, and the corresponding space 32 between the arms 30 and 31, permit the looped ends 41 of the tape members 13 and 14 to be readily slipped over or removed from the tape-securing arms. When the blind is in assembled condition, the tape members 13 and 14 extend linearly and outwardly from the looped ends 41, which are retained by the tape-securing arms 27, 28 and 30, 31, pass beneath and around the bars 36 and 39, and thence extend upwardly and perpendicularly from the rail 12. It will be seen that by this arrangement the direction of the tape members 13 and 14 is changed from a substantially horizontal to a vertical path whereby the weight of the rail 12 is carried to a large extent by the bars 36 and 39 around which the tape members pass. Thus, the full force due to the weight of the rail 12 and resulting during the tilting operation is not imposed upon the tape-securing arms 27, 28 and 30, 31 which, being rigidly secured at only one end, would tend to be bent or distorted upwardly from the plane of the bracket if the tape members 13 and 14 extended directly upwardly therefrom without first passing beneath the bars 36 and 39. By the present arrangement, the force which would otherwise tend to bend the arms 27, 28 and 30, 31 upwardly is converted to a substantially lateral or generally edgewise pull to which the relatively thin flat arms are obviously much more resistant in view of their integral formation with the flanges 22.

When the tape-securing bracket 10 is mounted on an upper rail or tilting rail, the forces acting on the tape-securing arms are even greater inasmuch as the upper brackets support the entire weight of the slats and bottom rail. Accordingly, the provision of the tape-engaging side bars 36 and 39 to diminish the load on the arms and to convert the forces from a direct downward pull to a generally sidewise of lateral force is even more important than in the case illustrated in the drawing where only the weight of the bottom rail is involved. It will be understood that when the bracket 10 is thus employed in combination with an upper horizontal rail (not shown) the tape members 13 and 14 will extend linearly and outwardly from the tape-securing arms, will pass over and around the side bars (instead of under the side bars), and will thence extend downwardly from the rail.

Although in the form of the invention shown herein, for purposes of illustration, the bars 36 and 39 are hingedly or pivotally attached to the ears 34, it is also within the scope of my invention to provide side bars which are integral at both ends with the flanges 22 or to provide connections at both ends of the bars 36 and 39 for rigidly or detachably securing the same to the ears 33 and 34. However, the pivotal mounting of the bars, as shown in the drawing, facilitates the operation of attaching or detaching the tapes as described below.

The lower end of the cord 18 is provided with an enlarged member or ferrule 42 crimped thereto, the ferrule being of dimensions such that it can be readily inserted through the enlarged portion 24 of the keyhole slot 23. When the cord 18 is thereafter moved sidewise into the narrow portion 25, the ferrule 42 engages the bottom edges of the slot for raising the blind when desired. The width of the restricted portion 26 of the slot 23 is such that the cord 18 must be compressed slightly to pass from the portion 24

to the elongated portion 25, the restriction 26 thereby serving to retain the cord 18 within the portion 25 to insure contact of the ferrule 42 with the bracket. If desired, other forms of cord retaining means or locking members may be employed, e. g. such as disclosed in my co-pending application Serial No. 71,516, filed January 18, 1949. If the bracket 19 is mounted on an upper rail, as hereinbefore referred to, the slot 23 may comprise merely an aperture to permit the cord 18 to extend freely therethrough and the upper rail per se will be provided with a similar and registering aperture. An additional recess 43 is provided in the lower surface of the recess 11 in the rail 12 and is of elongated character disposed beneath the keyhole slot 23 in order to provide room for vertical and side-wise movement of the end of the cord 18 and the ferrule 42 during attachment and detachment of the cord with respect to the bracket 10.

In order to detach the tape members 13 and 14 and the cord 18 from the bracket 10, the bottom rail 12 is first lifted to remove the weight from the tapes and cord. With the slack produced in the tapes 13 and 14 by lifting of the rail 12, clearance is thereby provided to permit swinging of the bars 36 and 39 to open position, as seen in Fig. 5, and the looped ends 41 of the tape members may then be removed by obvious manipulations from the tape-supporting arms through the spaces 29 and 32. To detach the cord 18, the cord is displaced sidewise through the restriction 26 to the enlarged portion 24 of the slot 23 in which position the ferrule 42 may then be withdrawn upwardly through the slot 23. The cord 18 and the corresponding cord at the other end of the blind having been detached and pulled upwardly, the slats of the blind may then be readily removed, and upon detachment of the tapes from similar brackets on the top rail of the blind, the tapes also are disconnected for washing or cleaning. It will be apparent that to reassemble the blind, the looped ends 41 of the tape members are slipped through the spaces 29 and 32 and the tape-securing arms inserted therethrough, the bars 36 and 39 are swung to closed position, the slats of the blind are inserted endwise between the tape members, and finally the cord is threaded downwardly through the slats and is secured in the slot 23 as hereinbefore described.

If, as hereinbefore mentioned, the tape-engaging side bars 36 and 39 are rigidly and permanently secured at both ends to the ears 33 and 34 instead of being pivotally secured at only one end, it will be necessary to thread the looped ends 41 of the tape members through the spaces between the bottom of the recess 11 and the bars 36 and 39 in order to attach the tapes to the arms 27, 28 and 30, 31. It will be apparent that the pivotal mounting of the bars 36 and 39 greatly facilitates the step of attaching the tape members to the bracket since the necessity for threading the tape members under the bars is thereby eliminated.

The tape-securing bracket comprising the present invention possesses a number of important advantages because the full weight of the blind or the bottom rail is not imposed directly upon the tape-securing arms, and the brackets may, therefore, be formed from relatively light gauge metal in a single stamping operation employing dies of comparatively simple construction. The provision of pivotally mounted tape-engaging side bars which are

adapted to bear a substantial portion of the load imposed upon the bracket avoids undesirable bending or distortion of the tape-securing arms. Furthermore, all stitching of the tapes at the looped ends thereof is effectively concealed by the side bars when in closed position thereby presenting a neat appearance.

It has been found that even if the bracket is formed from relatively heavy gauge metal with the side bars omitted and with the tapes extending directly from relatively stiff tape-securing arms of the character herein described comprising oppositely extending arms with a spaced portion between the free ends thereof, the result is an unsightly creased or bellied appearance running throughout a considerable portion of the length of the tapes due to the lack of support at the spaced portions between the arms. By avoiding direct vertical extension of the tapes from arms of this character, I also eliminate such unattractive and undesired creasing or bellying. By extending the tape members outwardly from the arms around the side bars and vertically therefrom, any bellying is confined to the concealed horizontal portions of the tapes and a smooth flat tape surface is provided on the vertical exposed portion which remains free of all undesirable wrinkles and creases even during use of the blind.

It will also be apparent that the brackets herein described are readily adapted for use with all types of Venetian blinds and are of such simple construction that the tapes and cords may be detached therefrom and re-attached thereto by simple operations requiring neither special tools nor any particular degree of mechanical ability.

Although my invention has been illustrated and described in connection with one particular embodiment thereof, it will be understood that various equivalent structures and modifications of the device may be resorted to without departing from the scope of the invention as defined in the appended claims.

I claim:

1. A bracket for detachably securing the ends of a slat-supporting tape to a rail of a Venetian blind, comprising a body member having a central portion adapted to be secured to a rail, spaced tape-securing arms disposed on opposite sides of said central portion and adapted to detachably retain the end portions of a tape, and a pair of elongated tape-engaging side members disposed outwardly of said arms, each of said side members being pivotally secured at one end thereof at opposite sides of said body member and adapted to be positioned in parallel, non-clamping, spaced relation with respect to said arms whereby to permit the tape members to extend from said arms, around said side members, and thence outwardly from the bracket, said side members being swingable about their pivoted ends to open position for facilitating attachment of the tape to and detachment thereof from said arms.

2. A bracket for detachably securing the ends of a slat-supporting tape to a rail of a Venetian blind, comprising a body member having a central portion adapted to be secured to a rail, spaced tape-securing arms disposed on opposite sides of said central portion and adapted to detachably retain the end portions of a tape, a pair of elongated tape-engaging side members disposed outwardly of said arms, each of said side members being pivotally secured at one end thereof at opposite sides of said body member, and means on said body member coacting with the free ends of said

side members for releasably holding the latter inwardly of the body member in parallel, non-clamping, spaced relation with said arms whereby to permit the tape members to extend from said arms, around said side members, and thence outwardly from the bracket, said side members being swingable outwardly from said body member to open position whereby to facilitate attaching and detaching the tape to and from said arms.

3. A bracket for detachably securing the ends of a slat-supporting tape to a rail of a Venetian blind comprising a body member having a central portion adapted to be secured to a rail, spaced tape-securing arms extending from said body member longitudinally of the rail on opposite sides of said central portion and adapted to detachably retain the end portions of a tape, spaced ear portions adjacent the opposite sides of said member in spaced relation from said arms, and a pair of elongated tape-engaging side members disposed outwardly of said arms, each of said side members being pivotally secured at one end thereof to one of said ear portions and having its opposite end free and adapted to engage and be supported by the oppositely disposed ear portion for retaining the side members in parallel, non-clamping, spaced position with respect to said arms whereby the tape members may extend linearly from said arms to said side members, around the latter, and thence vertically away from the bracket.

4. A bracket for detachably securing the ends of a slat-supporting tape to a rail of a Venetian blind, comprising a one piece body member having a flat central portion adapted to be fastened to a rail, integral flange members disposed at opposite ends of said central portion and extending laterally on each side thereof, said flange members being adapted to abut the sides of a recess in the rail, elongated tape-securing arms extending integrally from the edges of said flange members on each side of said central portion and spaced therefrom, said arms being adapted to detachably retain the end portions of a tape, ear portions adjacent the ends of said flange members and extending inwardly from the edges thereof in spaced relationship with said arms, said arms and said ear portions being substantially coplanar with said central portion, and a pair of elongated tape-engaging side members each pivotally secured at one end thereof to one of said ear portions and having its opposite free end adapted to engage the oppositely disposed ear portion for retaining the side members in parallel, non-clamping, spaced position with respect to

5. said arms whereby to permit the tape members to extend linearly from said arms to said side members, around the latter, and thence generally perpendicularly away from the plane of said body member.

5. A bracket for detachably securing the ends of a slat-supporting tape to a rail of a Venetian blind, comprising a one piece body member having a flat central portion adapted to be fastened to a rail, integral flange members disposed at opposite ends of said central portion and extending laterally on each side thereof, said flange members being adapted to abut the sides of a recess in the rail, elongated tape-securing arms extending integrally from said flange members on each side of said central portion and in spaced relation therefrom, said arms being adapted to detachably retain the end portions of a tape, ear portions extending inwardly adjacent the ends 10 of said flange members in spaced relation with said arms, and a pair of elongated tape-engaging side members in the form of bars having a generally U-shaped cross-section, each of said bars being pivotally attached at one end thereof to 15 one of said ear portions for swinging movement away from and toward said body member, and the opposite free end of each of said bars being adapted upon movement thereof toward said body member to receive the oppositely disposed ear 20 portion in frictional engagement within said 25 U-shaped cross-section whereby to retain said bars in position parallel to said arms in spaced non-clamping relation therewith thereby permitting the tape members to extend linearly from 30 said arms to said side members, around the latter, and thence generally perpendicularly away from the plane of said body member.
